United States Patent Office

Des. 207,996
Patented June 27, 1967

207,996

TELEPHONE DESK STAND

Howard Emlyn Upjohn, Berkhamsted, England, assignor
to The General Electric Company Limited, London,
England

Filed Feb. 28, 1966, Ser. No. 1,214

Term of patent 7 years

(Cl. D26—14)

Fig. 1

Fig. 2

Fig. 3

Fig. 4

Fig.5

FIG. 1 is a left-side, top and front perspective view of a telephone desk stand, showing my new design;

FIG. 2 is a right-side, top and rear perspective view; FIG. 3 is a top plan view;

FIG. 4 is a right-side elevational view, the left-side being substantially a mirror image thereof; and

FIG. 5 is a bottom plan view thereof.

I claim:

The ornamental design for a telephone desk stand, as shown and described.
